Attorney.

UNITED STATES PATENT OFFICE

HOWARD I. SCHRANKEL, OF BUFFALO, NEW YORK

HEATING APPARATUS

Application filed February 2, 1929. Serial No. 337,142.

This invention relates to improvements in heating apparatus and more particularly to an apparatus in which gas is used as the fuel.

Its chief object is the provision of an apparatus of this character which is efficient in operation, which produces an intense heat with a minimum consumption of fuel, and in which the gas and air are so introduced and combined as to afford practically perfect combustion.

A further object of the invention is to provide a gas-burning system for furnaces, boilers and the like, which is simple, compact and inexpensive in construction, and which can be readily installed without materially altering the present heating equipment.

In the accompanying drawings:—

Figure 1 is a fragmentary sectional view of a heating apparatus showing my improvements embodied therein. Figure 2 is an enlarged fragmentary longitudinal section of that part of the device wherein the gas and air are mixed to form the combustible mixture.

Similar characters of reference indicate corresponding parts throughout the several views.

While the invention is applicable to any form or type of heating apparatus, it has been shown, by way of example, in connection with the casing 10 of a hot air furnace. In the fire-box 11 of the furnace is a gas burner of any suitable and well known construction, that depicted in the drawings consisting of arcuate sections 12, 12 extending partially around the fire-box and supported on branch pipes 13 leading to a T or similar fitting 14 into which the combustible mixture of gas and air is introduced. The lower end of the fire-box or combustion chamber is preferably closed and sealed with a filling 15 of sand or like material.

The air for the mixture is introduced under comparatively high pressure from a suitable fan 16 driven by an electric motor or other source of power (not shown) and connected to its outlet end is an air line or pipe

17. The gas for the mixture is introduced under the usual service pressure from the meter (not shown) through a gas line or pipe

18 which is connected at its outlet end to a T-fitting 19 secured to the outlet end of the air pipe. To the other end of this fitting is joined a mixing chamber preferably in the form of a curved member or elbow-like fitting 20 connected to the T-fitting 14 by an upright mixture-conducting pipe 21. The curved portion of this elbow fitting constitutes a deflecting wall against which the proportionate volumes of gas and air impinge and become thoroughly mixed. Valves 22 and 23 in the air and gas lines serve to control the supply of these elements to the burners.

By this construction and arrangement of parts the gas is introduced into the air supply at a point immediately adjoining the mixing chamber and thoroughly mixed therewith before reaching the point of consumption at the burners. Furthermore, the introduction of the gas at the point shown in the drawings and the provision of the elbow results in a thorough and intimate intermingling of the two elements to produce a perfect combustible mixture, the disposition of the elbow causing a whirling action of the gas and air as it travels from a horizontal to a vertical path and momentarily baffling the flow of the gas and air to effectively cause a thorough blending thereof. This mixture passes under high pressure immediately to the burners and produces an intense heat with a minimum consumption of gas.

I claim as my invention:—

1. In a gas burning device of the character described, a burner, a mixture-conducting pipe connected thereto, a pipe for delivering air under pressure to the inlet end of said mixture-conducting pipe and disposed at substantially right angles thereto, a gas supply pipe connected to said air pipe at a point adjacent to its connection with the mixture-conducting pipe, the outlet end of said gas pipe terminating at the bore of the air pipe, and means interposed between the inlet end of the mixture-conducting pipe and the outlet end of said air pipe for effecting an intimate mixing of the air and gas.

2. In a gas burning device of the character described, a burner, a mixture-conducting pipe connected thereto, a pipe for deliv-

ering air under pressure to the inlet end of said mixture-conducting pipe and disposed at substantially right angles thereto, a gas supply pipe connected to said air pipe at a point immediate to its connection with the mixture-conducting pipe, the outlet end of said gas pipe terminating at the bore of the air pipe for delivering the gas radially thereof, and a connection between the inlet end of the mixture-conducting pipe and the outlet end of said air pipe, said connection including a deflecting wall against which the gas and air discharged from said air pipe are adapted to impinge and intimately mix before being delivered to the burner.

3. In a gas-burning device of the character described, a burner, a mixture-conducting pipe depending therefrom, a pipe for delivering air under pressure arranged at substantially right angles to said mixture-conducting pipe and having its outlet end disposed adjacent to the inlet end of the latter, a gas supply pipe connected to said air pipe adjacent its outlet end, and an elbow-like fitting connecting the inlet and outlet ends of the mixture-conducting pipe and the air pipe, respectively, and against the inner wall of which the gas and air are adapted to impinge to effect their intimate mixture, the distance between the burner and the elbow-like fitting being greater than the distance between the latter and the point of connection at the gas pipe to the air pipe.

4. In a gas burning device of the character described, a burner, a mixture-conducting pipe connected to the burner, a pipe for delivering air under pressure to said mixture-conducting pipe, a T-fitting connected to the outlet end of said air pipe, an elbow fitting constituting a mixing chamber connecting said T-fitting with the inlet end of the mixture-conducting pipe, and a gas supply pipe connected to said T-fitting for delivering the gas to said air pipe at a point immediately adjoining said elbow fitting, the outlet end of the gas pipe terminating at the bore of the T-fitting to provide a clear and unobstructed path for the air supply.

HOWARD L. SCHRANKEL.
